UNITED STATES PATENT OFFICE

JOHN F. ROBB, OF CLEVELAND HEIGHTS, OHIO, ASSIGNOR TO KOEHRING COMPANY,
OF MILWAUKEE, WISCONSIN, A CORPORATION

TRUCK MIXER

Application filed September 16, 1929. Serial No. 392,861.

Various mixers have been designed in the past few years for mixing concrete on a vehicle while the same is en route to a job. In order to discharge the mixed concrete at the place where it is to be used, the receptacle is generally provided with tilting means or conveying means to accomplish such discharge of the mixed aggregates. This discharge usually takes place at an appreciable height above the ground, necessitating the use of a chute in order to break the fall of the aggregates.

One of the objects of the instant invention is the provision of a receptacle for mixing concrete while transporting the same to its point of use, said receptacle having novel tilting means associated therewith whereby the discharge point of the aggregates therefrom may be brought as low as desired, even below the level of the surface upon which the vehicle is standing.

In carrying out my invention, I mount any suitable type of receptacle upon a truck body, the receptacle having a discharge opening in its rear wall. Novel means in the form of a rack and pinion are provided for moving the rear end of the receptacle back over the rear of the truck while at the same time the front end of the receptacle is raised. This results in a sliding and tilting movement, whereby the discharge opening may be brought as close to the ground as desired.

A further object of my invention is the provision of novel means for bringing about this sliding and tilting motion, said means being self-sustaining for holding the receptacle in any of its intermediate positions.

A further object of the invention is the provision of novel means whereby the contents of the receptacle may be agitated or mixed regardless of the position of the receptacle, said means being driven by a device located upon the vehicle, preferably the propelling means for the same.

Further and more detailed objects and advantages will in part become apparent and in part be hereinafter stated in the following description and appended claims.

For a full and more complete understanding of the invention, reference may be had

to the following description and accompanying drawings, in which—

Figure 1 is a view in side elevation of one embodiment of my invention.

Figure 2 is an end view with parts in section, taken about on the line 2—2 of Figure 1.

Figure 3 is a sectional view taken about on the line 3—3 of Figure 2.

Figure 4 is a view similar to Figure 3, but looking in the opposite direction, and is taken about on the line 4—4 of Figure 2.

Figure 5 is a diagrammatic showing of two of the positions which my receptacle may take.

While a preferred, specific embodiment of the invention is herein set forth, it is to be understood that I am not to be limited to the exact constructions illustrated and described, because various modifications of these details may be provided bringing the invention within the purview of the appended claims.

Throughout the following description and various figures of the drawings, like reference characters denote corresponding parts.

In the drawings any desirable type of truck A having frame members 1 is provided with a mixing drum 2. The mixing drum 2 may be of any familiar construction, having the paddles or agitators 3, charging opening 4, and discharge opening and door therefor 5. The mixing drum 2 is supported by any suitable type of bearings 6 which bearings permit rotation of the drum therein and also prevent longitudinal movement of the drum in respect thereto. The bearings 6 are secured to a framework 7 by means of brackets 8 substantially as shown. Secured to the framework 7 and extending lengthwise beneath the drum 2 are racks 9 having the teeth thereof on the underside.

The rear end of the frame 1 of the vehicle A is provided with openings through which a shaft 10 extends, said shaft having secured thereto pinions 11 which engage the teeth of the racks 9 and support the rearmost portion of the drum 2 and its associated parts. In the position shown in Figure 1 the forward part of the framework 7 rests upon the cross piece shown at 12, thereby holding the drum 2 in its horizontal position. A worm gear 100

13, also secured to the shaft 10, meshes with a worm 14 secured to the shaft 15 which is driven by the motor of the truck or vehicle A. A suitable transmission and operating lever 16 therefor are associated with the shaft 15 for controlling the rotation thereof. A shaft 17 is rotatably mounted on the frame 1 at some point intermediate its length. Secured to the shaft 17 are arms 18, the other ends of which are pivotally connected to the racks 9 as shown at 19. It can readily be seen that rotation of the pinions 11 causes movement of the drum 2 longitudinally of the truck A, which longitudinal movement is accompanied by a raising of the forward end of the drum by reason of the pivotally mounted arms 18.

In order to make the drum self-sustaining in any of its positions, and also to cause the arms 18 to actively contribute to the lifting of the drum, the shaft 17 is provided with a worm gear 20 which meshes with the worm 21 on a shaft 22. The shaft 22 is driven by shaft 10 through a pair of bevel gears denoted 23. Rotation of shaft 10 causes a corresponding rotation of the shaft 17 through the train of gears as above described, rotation of shaft 17 in turn causing movement of the arms 18. The worms 14 and 21 and their corresponding worm gears 13 and 20 make it impossible for the drum 2 to return to its horizontal position under its own weight. Movement of the drum 2 in either direction must be accomplished by proper rotation of the shaft 15.

To prevent disengagement of the racks 9 from the pinions 11, brackets 24 are rotatably mounted on the shaft 10, which brackets in turn carry rollers 25 which bear against the upper surface of the framework 7.

The shaft 17 has a double sprocket 26 loose thereon, and a shaft 27 passing through the pivotal point 19 has a single sprocket 28 mounted thereon. One part of the double sprocket 26 is connected to the sprocket 28 by means of a chain 29, while the other part 45 of the sprocket 26 is connected to a similar sprocket 30 by means of the chain 31. The sprocket 30 may be driven as desired by proper manipulation of the transmission lever 16. A worm gear 32 secured to the shaft 50 27 engages a ring gear 33 on the mixer drum 2.

The operation of the device is as follows:— The drum 2 is filled with the proper aggregates and water for forming the batch of concrete. The transmission lever 16 is then moved in the proper position to cause driving of the sprocket 30 which in turn causes rotation of the drum 33 by means of the chain 31, double sprocket 26, sprocket 28, shaft 27, and worm 32. Since the sprockets 26 and 28 55 are mounted in alignment with the pivotal points of the arms 18, the distance between these sprockets will always be the same and driving of the drum may be maintained during movement of the same as well as when 60 it is in a horizontal position. When the place

in which the concrete is to be used is reached, the lever 16 is positioned so as to drive both the sprocket 30 and the shaft 15, whereupon the drum continues rotating as it is lifted and slid backwardly upon the truck A. When the discharge opening 5 of the drum has reached the proper level, the lever 16 may be once more shifted so that raising of the drum discontinues, but rotation thereof does not stop. As has been before pointed out, the drum will be self-sustaining in any of its raised positions. After the concrete has been discharged, proper manipulation of the lever 16 will once more bring the drum to the position shown in Figure 1 and discontinue rotation of the same.

Having thus described my invention, what I claim as new and desire to secure by Letters Patent of the United States, is—

1. A truck mixer of the class described, comprising, in combination, a vehicle, a mixing drum mounted on the vehicle for receiving aggregates, means for tiltably and slidably moving said drum in respect to said vehicle, whereby said aggregates may be discharged, and means for rotating said drum to mix said aggregates, said means being operatively connected to a driving means located on the vehicle and operable during tilting and sliding movements of said drum. 90

2. A truck mixer of the class described, comprising, in combination, a vehicle, propelling means therefor, a mixing drum mounted on the vehicle for receiving aggregates therein, means for tiltably and slidably moving said drum in respect to said vehicle, said means being operatively connected with the propelling means, and means also operatively connected with said propelling means for rotating said drum to mix 100 said aggregates, said rotating means being operable during the sliding and tilting movements of said receptacle.

3. A truck mixer of the class described, comprising, in combination, a vehicle, a mixing drum rotatably mounted thereon, said mixing drum also being tilttable and slidable in respect to said vehicle, means for tilting and sliding said drum, means for rotating the same during tilting and sliding movements thereof, and a driving device for said rotating means, said device being located on said vehicle. 110

4. A truck mixer of the class described, comprising, in combination, a vehicle, a receptacle mounted thereon and having a discharge opening, and means for simultaneously slidably, tiltably, and rotatably moving said receptacle in respect to said vehicle whereby the contents of said receptacle may 120 be completely discharged.

5. A truck mixer of the class described, comprising, in combination, a vehicle, a mixing drum, a rack secured to said drum, a pinion mounted on said vehicle and engaging 130

said rack, means for driving said pinion for sliding said drum in respect to said vehicle, and devices operable incident to sliding of said drum for simultaneously tilting and rotating the same.

6. A truck mixer of the class described, comprising, in combination, a vehicle, a rotatable mixing drum mounted thereon, means to cause inclination of the drum, means for 10 moving said drum in an inclined plane relatively to said vehicle, whereby discharge from the drum will be at a point below the surface upon which the vehicle rests, and means to rotate the drum.

15 7. A truck mixer of the class described, comprising, in combination, a vehicle, a rack thereon, a receptacle secured thereto, a pinion mounted on said vehicle and engaging said rack, a worm for driving said pinion, 20 an arm having its respective ends pivoted to the receptacle and the vehicle, a worm gear having its axis in alignment with the pivotal mounting of said arm on the vehicle, the arm and worm gear having a connection therebetween, a worm for driving said worm gear, 25 the worm being driven from said pinion and means for driving the pinion.

8. In a truck mixer of the class described, the combination with a vehicle, a mixing 30 drum thereon for the reception of aggregates, the drum being tiltable and rotatable for the discharge of said aggregates, and means for rotating the drum to mix the aggregates, of driving devices for said means, said devices 35 transmitting motion from the vehicle directly to the end of the receptacle which is raised and rotated during discharge of the aggregates.

9. A truck mixer of the class described, 40 comprising, in combination, a vehicle, a receptacle thereon, means for tilting the receptacle, said means including an arm, the respective ends of which are pivoted to the vehicle and the receptacle, and means for 45 mixing the contents of said receptacle, said means including a gear mounted in alignment with each of the pivotal points of said arm, whereby said means is operative during tilting of said receptacle.

50 10. A truck mixer of the class described, comprising, in combination, a vehicle, a receptacle thereon, means for tilting the receptacle, said means including an arm pivotally connected at one end to the vehicle and 55 at the other end to the receptacle, motor means for turning the receptacle mounted on the vehicle, and operating connections between the motor means and the receptacle for rotation of the latter, including driving parts 60 coaxial with the pivotal connections at the ends of said arm.

11. A truck mixer of the class described, comprising, in combination, a vehicle, a receptacle mounted thereon and having a discharge opening, means to simultaneously

slide and tilt the receptacle relatively to the vehicle to discharge said receptacle, and means to rotate the receptacle to mix its contents while said receptacle is being slid and tilted as above described.

70

In testimony whereof I affix my signature.
JOHN F. ROBB.
